(Cl. D49—1)

Fig. 1

Fig. 3

Fig. 1 is a perspective view of a laundry appliance cabinet showing my new design and illustrating the front and one side thereof;

Fig. 2 is a view similar to Figure 1 but illustrating the doors in an open position; and

Fig. 3 is a side elevational view of the laundry appliance cabinet.

The dominant features of the design reside in the portions disclosed in full lines.

I claim:

The ornamental design for a laundry appliance cabinet or similar article, as shown and described.
